WASHING AND DRY CLEANING MACHINE

Herbert C. Bowen, Detroit, Mich., assignor to
Bendix Home Appliances, Inc., Detroit, Mich.,
a corporation of Delaware

Application March 12, 1937, Serial No. 130,444

10 Claims. (Cl. 68—18)

The present invention relates to improvements in washing machines and particularly to washing machines comprising a receptacle adapted to be supplied with suitable liquid and the liquid drained therefrom while the receptacle is sealed.

In apparatus of the above type the liquid customarily used is water and along with the water is used a suitable detergent, such as soap. When the water is added to the sealed receptacle, in 10 which soap has been previously placed, the air contained therein is compressed and tends to cause leakage of water as well as the soap bubbles that are formed during the time liquid is added and during agitation of the textiles. To prevent 15 this leakage the receptacles have been provided with an air vent whereby the air pressure within the receptacle is maintained at atmospheric pressure at all times.

The principal object of the present invention is 20 to provide a new and improved air venting means providing a pressure-equalizing means preventing leakage of soap bubbles or other liquid entrained in the air passing through said venting means.

A more specific object of the present invention 25 is to provide a venting means adapted to permit flow of air therethrough into or out of the receptacle and to return back into the receptacle all entrained liquid flowing out of the receptacle.

A further object of this invention is to provide 30 a new and improved air vent adapted for use with apparatus utilizing liquid level controlled means for maintaining a predetermined amount of liquid within the receptacle.

In the drawings:

35 Fig. 1 is a front elevation, partly in section, of a washing machine embodying the present invention. The door through which textiles are placed into and removed from the machine has been omitted from this figure for the purpose of better showing other features;

40 Fig. 2 is a top plan view, also partly in section, of the apparatus shown in Fig. 1;

45 Fig. 3 is an enlarged elevation, partly in section, of the liquid level controlling means of Figs. 1 and 2; and

50 Fig. 4 illustrates diagrammatically a form of control that may be used with the apparatus.

These specific drawings and the specific description thereof that follows are merely to illustrate an illustrative embodiment of the invention and are not to be construed as imposing limitations on the claims.

The machine disclosed herein by way of example is a domestic washing machine, although the 55 invention is equally applicable to dry cleaning

and commercial machines. Referring particularly to Figs. 1 and 2, it may be seen that the machine has a base 10, consisting of a square angle, which supports an upright frame 12 having substantially the shape of a right angle triangle. At its apex the frame carries a pair of bearing supports 14 in which is journaled a shaft 16. The shaft is mounted in cantilever fashion and is turned by a pulley 18 keyed or otherwise secured thereto between the bearing supports 10 and driven through a belt 20 by an electric motor 22 mounted on base 10. The motor may be supplied with energy from any suitable source and its energization controlled in any well known manner.

15 A washing drum or cylinder 24 adapted to contain textiles or other materials to be washed is mounted for rotation by shaft 16 which is provided with a hub 26 to which the drum is secured. The rear panel of the drum is provided with inwardly projecting ribs 28 and the periphery of the drum is provided with inwardly projecting baffles 30 for the purpose of increasing the efficiency of the washing action. The periphery is preferably provided with perforations 32 in accordance with usual practice.

20 The rotatable drum 24 is surrounded by an imperforate liquid-tight receptacle or tub 34 supported at its rear by frame 12 in a manner not shown. The tub in turn may be surrounded by 25 an upright cabinet 36 of pleasing design mounted upon base 10.

25 The textiles are placed into and removed from the rotatable drum through aligned centrally located circular openings provided on the front 30 walls of the cabinet, tub and drum, respectively. The opening in the drum is left open during operation, but the openings in the tub and cabinet are sealed against leakage of water and air by a door 38 adapted to bear against an annular 35 U-shaped flange 40 (see Fig. 2) uniting the front walls of the tub and cabinet at their respective openings.

30 Tub 34 is provided at its bottom with a sump 42 from the lowest point of which leads a drain 45 conduit 44 provided with suitable means, such as the valve 45, for controlling the drainage of liquid from the tub. The valve 45 is, of course, closed during the time the machine is in operation.

35 Liquid may be supplied to the tub from a suitable source through conduit 46 under the control of a flow-regulating means such as the electro-magnetically operated, normally closed valve 48. A flexible conduit 50 leads from the valve to a 40

nipple 52 opening into the space between the drum 24 and receptacle 34 and secured to the latter.

In the embodiment illustrated in the drawings, the liquid supplied to the machine is under the control of liquid level responsive means indicated generally by reference numeral 54. This means comprises a float chamber 56 secured to the tub 34 by welding 58 and connected at its bottom to the bottom of the tub by a relatively small diameter horizontally disposed conduit 60. Conduit 60 opens into the tub 34 through a tangential passageway 62 leading in the direction of rotation of drum 24, indicated by the arrow in Fig. 1. The passageway 62 is formed by a baffle plate 64 suitably secured to the inner side of tub 34 and formed with a curved portion 66 corresponding to the opening in the tub wall. The forward edge of the baffle plate 64 is provided with a small opening 68 providing a communicating passage between the front and rear sides of the baffle plate. The opening 68 serves to equalize the fluid pressure within passage 62 and conduit 60 with that in the tub and thus to prevent the rotation of the drum from pumping water from conduit 60 and the float chamber 56.

Mounted for vertical movement within the float chamber 56 is a ball float 70 spaced from the side walls of the chamber by vertical inwardly projecting guiding ridges 72 formed on the latter. A control rod 74 is attached to the top of the float 70 and it extends upward through a dished cover 76 provided with an opening 78 of greater diameter than the diameter of the rod for a purpose to be described hereinafter. The control rod 74 is adapted to impart movement through a lost motion connection 80 to the operating arm 82 of a snap acting switch 84, of any desired type.

The switch 84 is in circuit with the operating coil 86 of the normally closed inlet valve 48, as illustrated in Fig. 4. From this figure it may be seen that a manually operable switch 88 may be placed in series with the switch 84 and the coil 86. When switch 88 is closed to place the inlet valve under control of the level responsive means 54, then if the tub 34 is empty or the level of liquid below a predetermined value, an energizing circuit for the operating coil 86 of valve 48 will be closed by switch 84, which is in the position illustrated in Fig. 4.

As water is supplied to the tub the level gradually rises and float 70 is raised thereby. When the level reaches a predetermined value, control rod 74 moves the switch operating arm 82 to open switch 84 and thereby close the valve. When the water level thereafter recedes below a predetermined minimum value, the switch 84 is opened in an obvious manner to again open valve 48. It should be noted that utilization of a snap action switch operated by a lost motion mechanism permits variation of the liquid level between certain limits before the switch is actuated, as distinguished from a point control. This arrangement prevents operation of the valve in case of slight fluctuations in level that may be occasioned in normal operation of the machine.

In order to prevent the building of undesired air pressure in the tub 34 when liquid is supplied thereto after the soap and textiles have been placed therein, the tub is provided, in accordance with the present invention, with an outlet in the form of a vertical stack 90. The stack is mounted on the side wall of the tub 34, approximately diametrically opposite the float chamber 56 at a point approximately midway between the hori-

zontal axis and top of the tub on the side where the drum 24 rotates in a downwardly direction. Thus, water thrown away from the drum by centrifugal force has a downward component and is prevented from entering the stack 90. The entrance of water into the stack is prevented further by a downwardly extending baffle 92 which is secured to the leading edge of the opening.

The stack is closed at its top by a cover 94 and from a point near the top there leads a rearwardly and downwardly extending tube 96 connected at its lower end to the upper end of the float chamber 56.

It is apparent from the above description that the stack 90, tube 96, and float chamber 56 provide a vent to the atmosphere by means of which the pressure within the sealed tub 34 is maintained at atmospheric pressure at all times. The air exhausted to the float chamber 56 is free to escape to the surrounding atmosphere through the annular space between the control rod 74 and the cover 76 of the float chamber which, as stated previously, is provided with an opening 78 having a greater diameter than the rod. By having the upper portion of the float chamber, as well as the interior of the tub, at atmospheric pressure the operation of the liquid level control is improved as both chamber will be at the same air pressure.

In operation, textiles or other materials to be washed are placed into the rotatable drum 24 along with a suitable detergent such as soap. The door 36 is then closed to seal the surrounding imperforate tub 34. The motor 22 is then energized as by connection to a suitable source of energy, and manually operable switch 88 is closed to place the electromagnetically operated inlet valve 48 under control of the float switch 84. Energization of the motor results in the rotation of the drum 24 whereby the textiles therein are tumbled in a manner well known to those skilled in the art. Normally no water is present in the tub when switch 88 is closed and, therefore, float 70 would be at the bottom of the float chamber and snap switch 84 is closed. Thus, the operating coil 86 of the inlet valve 48 is energized by closure of switch 88 and the valve opened to admit liquid to the tub through conduit 60 and nipple 52. It should be understood that the drain conduit 44 is closed during the washing operation to prevent escape of the water from the tub.

The liquid level in both the tub 34 and float chamber 56 rises at an equal rate as both are open to the atmosphere and the float 70 is raised. After a predetermined liquid level obtains the latter actuates the snap switch 84 to its open position, thereby deenergizing the operating coil 86 of the inlet valve 48 and shutting off the supply of water.

As the liquid level within the tub 34 rises, the air contained therein is continuously displaced and readily escapes through stack 90 and tube 96 to the upper part of the float chamber 56 and thence to the atmosphere through the opening 78 between the control rod 74 and top 76 of the float chamber. Thus, no undesired pressure obtains within the tub as water is supplied thereto and the leakage of water is kept to a minimum.

During the continued agitation of the textiles by rotation of the drum 24, the interior of the drum and tub is filled with soap suds, and as the tub is being filled with water these may be entrained in the escaping air and be carried 75

out of the tub. However, all liquid so entrained is returned to the tub through the stack 38 and tube 36 where the bubbles are broken and the air thereby separated from the liquid. Consequently, the condensed liquid will drip from the lower end of the tube 36 into the float chamber 38 and be returned to the tub 34 while the released air will escape to the outside through the vent 78 around the switch control rod 74.

10 After the textiles have been washed the switch 38 is opened, motor 22 deenergized, and the water drained from the tub through conduit 44. As the water level recedes there is a tendency for a partial vacuum to be created in the tub, but air readily finds its way into the tub through the above described vent; consequently, the door 38 may be opened with ease and the textiles removed.

15 The described invention is not applicable solely to machines of the type described, but may be applied to washing or related types of machines generally in order to prevent undesired leakage of water therefrom. Thus, it may be utilized in machines not entirely sealed nor having automatic liquid supply, and to machines mounted for rotation on a vertical axis. Modifications and applications of the invention other than those described may occur to those skilled in the art and it is intended that the following 20 claims cover all these within the scope of the present invention. Except for the features claimed below, the machine illustrated in the drawings is the invention of Rex Earl Bassett, Jr. and John W. Chamberlin, and is claimed in 25 their applications Nos. 6,425, filed February 14, 1935, and 129,429, filed March 6, 1937.

30 I claim:

1. In combination, a receptacle adapted partially to be filled with liquid, a drum adapted to contain textiles mounted for movement within said receptacle, a float chamber in communication with the liquid-containing portion of said receptacle, means for controlling the level of liquid in said receptacle including a float in said 35 chamber, a stack opening from said receptacle above the level of the liquid therein, and a conduit connecting said stack and said float chamber.

2. In a washing machine, the combination including a receptacle adapted partially to be filled with liquid and sealed during operation, a drum adapted to contain textiles mounted for movement within said receptacle, and means including a chamber open to the atmosphere and in 40 communication with the liquid-containing portion of said receptacle and a portion of the receptacle above the normal liquid level for maintaining the interior of said receptacle at atmospheric pressure and preventing leakage of liquid 45 from said receptacle.

3. In a washing machine, the combination including a receptacle adapted partially to be filled with liquid and sealed during operation, a drum adapted to contain textiles mounted for rotation within said receptacle, means for rotating said drum in one direction, and means including a stack communicating with the receptacle above the normal liquid level on the side where the 50 rotation of the drum is in a downward direction, a chamber vented to the atmosphere and communicating with the receptacle below the normal liquid level, and a conduit communicating between the said stack and said vented chamber, for maintaining the interior of said receptacle

5 at atmospheric pressure and preventing leakage of liquid from said receptacle.

4. In combination, a substantially circular receptacle adapted partially to be filled with liquid, a drum adapted to contain textiles mounted for rotation within said receptacle, means for rotating said drum in one direction, and means including a chamber in communication with the liquid containing portion of said receptacle through a first conduit and with the portion 10 above the liquid through a second conduit for preventing leakage of liquid from said receptacle, and a baffle plate in the receptacle covering the opening of the first conduit and constructed to form with the inner periphery of the receptacle, 15 a tangential passage opening in the direction of rotation of the drum.

5. In combination with a washing machine having a receptacle, a drum mounted for rotation about its axis within the receptacle, means 20 for rotating said drum in one direction, and a chamber communicating with the receptacle above the normal liquid level and also with an opening in the liquid-containing portion of the said receptacle, a baffle plate in the receptacle 25 covering the opening communicating with said chamber and constructed to form with the inner periphery of the receptacle a tangential passage opening in the direction of rotation of the drum, said plate having a relatively small opening at 30 the end of said tangential passage opposite said first mentioned opening.

6. In a washing machine, the combination including a receptacle adapted partially to be filled with liquid and sealed during operation, a drum adapted to contain textiles mounted for rotation about its axis within said receptacle, means for rotating said drum in one direction, and means including a stack communicating with the receptacle above the normal level of the liquid 35 and on the side where the rotation of the drum is in a downward direction, a chamber vented to the atmosphere communicating with the liquid-containing portion of the receptacle through a conduit, and communicating with the stack 40 through a second conduit, for maintaining the interior of said receptacle at atmospheric pressure and preventing leakage of liquid from said receptacle and a baffle plate in the receptacle 45 covering the opening of the first named conduit 50 and constructed to form with the inner periphery of the receptacle a tangential passage opening in the direction of rotation of the drum.

7. In a washing machine, the combination including a receptacle adapted partially to be filled with liquid and sealed during operation, a drum adapted to contain textiles mounted for rotation about its axis within said receptacle, means for rotating said drum in one direction, and means including a stack communicating 55 with the receptacle above the normal level of the liquid and on the side where the rotation of the drum is in a downward direction, a chamber vented to the atmosphere communicating with the liquid-containing portion of the receptacle a baffle plate in the receptacle covering the opening communicating with said chamber and constructed to form with the inner periphery of the receptacle, a tangential passage opening in the direction of rotation of the drum, said 60 plate having a relatively small opening at the end of said tangential passage opposite the first mentioned opening, said chamber also communicating with said stack through a conduit, for maintaining the interior of said chamber at 65

atmospheric pressure and preventing leakage of liquid from said receptacle.

8. In combination, a receptacle adapted partially to be filled with liquid, a drum adapted to contain textiles mounted for movement within said receptacle, means including a chamber in communication with the liquid-containing portion of said receptacle and the portion of the receptacle above the normal liquid level for preventing leakage of liquid from said receptacle, and means including a float in said chamber for controlling the level of liquid in said receptacle.
9. In combination, a receptacle adapted partially to be filled with liquid, a cylinder mounted for rotation within said receptacle, means for rotating said cylinder in one direction, a float chamber, means providing communication between the float chamber and the liquid-containing part of said receptacle, and means including a float in said chamber for controlling the level of liquid in said receptacle, the means provid-

ing communication between the float chamber and liquid-containing part of said receptacle comprising a passage opening into said receptacle in the direction of rotation of said cylinder.

10. In combination, a receptacle adapted partially to be filled with liquid, a cylinder mounted for rotation within said receptacle, means for rotating said cylinder in one direction, a float chamber, means providing communication between the float chamber and the liquid-containing part of said receptacle, and means including a float in said chamber for controlling the level of liquid in said receptacle, the means providing communication between the float chamber and liquid-containing part of said receptacle comprising a pair of different sized passages opening into said receptacle in opposite directions, the larger sized passage opening in the direction of rotation of the cylinder and the smaller sized opening in the opposite direction.

HERBERT C. BOWEN.
